UNITED STATES PATENT OFFICE.

DAVID GRAVEL, OF CHATTANOOGA, TENNESSEE, ASSIGNOR TO THE STANDARD-COOZA-THATCHER COMPANY, OF CHATTANOOGA, TENNESSEE, A CORPORATION OF TENNESSEE.

SLUB CATCHER.

Application filed April 23, 1928. Serial No. 272,325.

My invention relates to slub catchers, and it is an object of the invention to provide a device which will catch slubs above a predetermined size, and will operate to stop the travel of the yarn when a slub larger than a predetermined size is encountered.

The device shown in this application closely resembles that shown and described in my co-pending application Serial Number 672,100, filed November 3, 1923, and is a continuation in part of that application.

Referring to the accompanying drawings which are made a part hereof and on which similar reference characters indicate similar parts,

Figure 1 is a plan view of the invention, Figure 2, a view in elevation,

Figure 3, a section on line 3—3 of Figure 1,

Figure 4, a section on line 4—4 of Figure 20 1, and

Figure 5, a detail view showing the slub catcher plate.

In the drawings reference character 10 indicates a support having an opening and a set 25 screw 11 projecting into the opening by means of which the support may be secured to a rod on a spooler or other textile machine. The support may be formed in various ways, that illustrated being a form which I consider desirable. At the right hand or forward end it has a projection 12 providing means for guiding the yarn into a notch 13 from which it passes back over the flat upper face of the support underneath a tension disc 35 14 and a slub catching plate 15.

The tension disc 14 is rounded on its under side for easy entry of the yarn beneath the disc and supported for rotation about a post 14'. An arched guide 16 extends over the 40 disc and post. The point 17 of said guide preferably extends below the upper face of the disc. It will be seen that this provides a quick and easy method of entering the yarn under the disc, since the yarn may be laid on 45 any part of the arch and slid down along the same, whereupon it will automatically slip under the disc.

The arch 16 is fastened by a set screw 18 to a bar 19 in the form of a leaf spring, which 50 is secured by a bolt 20 on an elevation 21 at one corner of the support 10. Preferably as here shown, the upper and under surfaces of the elevated corner section form parallel oblique surfaces and the spring has an oblique 55 part to correspond therewith, the main part

of the spring being approximately horizontal. The left end of the spring is free to move to a certain extent, such movement being limited by a screw 22 passing through an opening in the spring into the support 10. 60 Near this support is a bracket 23 having a hole through which the spring bar 19 passes, a bracket being adjustably secured thereto by set screws 24.

At the end of the bracket 23 remote from the spring support there is a pair of depending arms 25 through which the pivot pin 26 passes by means of which pivot pin the rectangular slub catcher 15 is supported on the bracket. The slub catcher 15 has a notch or 70 groove 15' extending across its face at a point just beneath the pivot 26. The screw 22 forms a rough adjustment for limiting the upper position of the slub catcher, while the screws 24 form a fine adjustment for positioning the same.

In the use of my device the disc 14 and the 75 guide 16 are positioned as shown in the drawings and the slub catcher is set at a distance from the support corresponding to the thickness of the yarn. The yarn is then entered through the notch 13, laid on the arch 16 and slipped under the tension disc 14 and the slub catcher 15. As the yarn passes over the face of the support it will rotate the disc in known manner and the knots by which the yarn is tied together will slip under the slub catcher between the face of the catcher and the face of the holder 10. Loose fluffs on the yarn will be pulled off by the disc and the plate 15, if 80 the quantity is small and if it does not adhere too tightly to the yarn. Any slub of sufficient size to be objectionable to the yarn will cause the plate to tilt about its pivot 26 and to catch the yarn so as to break it. Thereupon, the slub 85 may be removed and the yarn ends tied together, after which the winding or other operation may be resumed.

The device of my invention is not intended to stop the thread or yarn upon the appearance of any and all inequalities, but only upon the appearance of inequalities of such a nature that they are objectionable, as where a slub is sufficiently thick or very long, so as to make trouble in subsequent operations. A 90 single knot will ordinarily not be objectionable, such knots being necessary for the reason that the yarn from a number of spinning bobbins is wound on a single spool. A 95 single knot will lift applicant's pivoted plate 100 105 110

15 at the entering side and pass under the pivoted plate across the groove 15' to the reverse side, where it will tilt the plate in the reverse direction as the knot passes out at the 5 leaving side.

While I have shown the plate 15 as pivoted, I have found under certain circumstances that a plate rigidly secured as the plate 15 will operate. Under these circumstances the 10 long objectionable slubs are caught by frictional contact between a surface of the plate 15 and the face of the support 10. However, I find the pivoted plate most satisfactory and is the form generally used.

15 It will be obvious to those skilled in the art that various changes may be made in my device without departing from the spirit of the invention, and I, therefore, do not limit myself to what is shown in the drawings and 20 described in the specification, but only as set forth in the appended claims.

Having thus fully described my said invention, what I claim as new and desire to secure by Letters Patent is:

25 1. A slub catcher comprising a support, means for guiding the yarn over a face of the support and a plate adjacent said face swingable on a pivot transverse to the line of movement of said yarns, said plate having 30 parts extending in opposite directions from said pivot over the running yarn for tilting the plate on the occurrence of long slubs or other imperfections, to catch and break the yarn, substantially as set forth.

35 2. In combination a support, means for guiding yarn over a face of the support, a spring bar attached to an elevation on the support, a member carried by the spring bar adjacent said face of the support, said member co-acting with said face to arrest enlargements on the yarn, substantially as set forth.

40 3. A slub catcher comprising a support, means for guiding the yarn over a face of the support, a spring bar attached to an elevation on the support, a member carried by the spring bar adjacent said face of the support and co-acting therewith to catch slubs and the like, and means at the free end of the 45 spring bar for adjusting it towards said face, substantially as set forth.

45 4. A slub catcher comprising a support, means for guiding yarn over a face of the support, a spring bar attached to an elevation on the support, a bracket on the spring bar, 50 a member carried by the bracket adjacent said face of the support, means for adjusting the free end of the spring toward and from said face, and means for adjusting the bracket toward and from said face, relative to the 55 spring bar, substantially as set forth.

55 5. The combination of means for guiding a running yarn, a pivoted member at one side of said yarn, and a member at the opposite side of the yarn adapted to co-operate with 60 the pivoted member in clamping the yarn at

opposite sides of the pivot of said pivoted member, substantially as set forth.

6. The combination of means for guiding a running yarn, a pivoted member at one side of said yarn, and a member at the opposite side of the yarn adapted to co-operate with 70 the pivoted member in clamping the yarn at opposite sides of the pivot of said pivoted member, said members having opposed flat faces, substantially as set forth. 75

7. The combination of a plate, means for guiding a yarn over a face of the plate, and a pivoted plate having a face parallel to said face of the first-named plate, said plates 80 being adapted for yarn-clamping engagement at either side of said pivot, substantially as set forth.

8. The combination of means for guiding a 85 yarn, a pair of plates having opposed faces between which said yarn runs said plates having relative pivotal movement about an axis parallel to their opposed faces, and means on said plates adapted to clamp the 90 yarn simultaneously at opposite sides of said axis on the occurrence of objectionable irregularities in the yarn, substantially as set forth.

9. A slub catcher comprising a support, means for guiding yarn over a face of the support, a plate pivotally mounted above said 95 support, having its face substantially parallel to the face of the support, the said plate having a transverse groove parallel to the pivoted support of the plate, substantially as 100 set forth.

10. A slub catcher comprising a support, means for guiding yarn across the face of said support, a plate pivotally mounted above said support, the said plate having a groove across 105 its face parallel to the axis of the pivots in which the plate is supported and beneath said axis, whereby enlarged portions of the yarn may tilt the plate upon entering beneath it, pass across the said groove and tilt the plate in the opposite direction as the obstructions 110 pass from beneath the plate, substantially as set forth.

11. A slub catcher comprising a support, a plate pivotally mounted on a pin above said support and having its face parallel to the 115 face of the support, means for adjusting the plate toward and from said support, the said plate having a groove cut in its face parallel to the axis of and substantially beneath said pin, substantially as set forth. 120

12. A slub catcher comprising a base, means for moving a yarn across said base, a plate pivotally supported above said base having its face substantially parallel with the face of the base, a transverse groove in 125 said plate, located substantially beneath and parallel with the axis of the supporting pivots of the plate, means for adjusting the said pivoted plate toward and from the base, substantially as set forth. 130

13. A slub catcher comprising a support, means for moving a yarn across said support, a plate mounted above said support, the said plate having means for adjusting it toward 5 and from said support, substantially as set forth.
14. A slub catcher comprising a support, means for guiding the yarn over a face of the support, a plate pivoted adjacent said face in 10 position to be tilted by a slub, means whereby a single slub will be permitted to pass said plate, and means whereby two or more adjacent slubs will be retained by said plate to break the yarn, substantially as set forth.
15. The combination of a support, means 15 for guiding yarn over the support, a yarn tension disc on the support, a bracket on the support, a pivoted plate on the bracket adapted to allow small or spaced slubs to pass freely and to retain large or closely arranged slubs, 20 thereby breaking the yarn, substantially as set forth.

In witness whereof, I have hereunto set my hand at Chattanooga, Tennessee, this 19th day of April, A. D. nineteen hundred and 25 twenty-eight.

DAVID GRAVEL.
